UNITED STATES PATENT OFFICE

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY

BURNISHING MACHINE

Application filed January 5, 1928. Serial No. 244,747.

This invention relates to burnishing machines and is herein illustrated as embodied in a heel burnishing machine of the type illustrated in Letters Patent of the United States No. 743,988, granted Nov. 10, 1903, upon the application of Charles Pease, although in various respects the invention is not limited to embodiment in heel burnishing machines.

In the operation of burnishing the leather heels of both men's and women's shoes, machines of the type illustrated in the above mentioned Letters Patent have long been used successfully. These machines are arranged to apply a coating of carnauba wax by means of a rotary metallic burnishing tool having a coating of melted wax for application to the surface of the work. This melted wax is supplied to the tool from a heated wax pot by means of a wax transferring wheel. Such machines are also usually supplied with a cloth covered brush or pad, a beading tool, and a polishing brush for use successively after the work has been treated by the burnishing tool.

One object of the present invention is to provide an improved burnishing machine by means of which the quality of work produced may be improved and the quantity of work increased and which will be more convenient for the operator.

To this end and in accordance with a feature of the invention, the illustrated heel burnishing machine is provided with a burnishing tool and a wax transferring wheel mounted for relative lateral adjustment so that they may be brought into that cooperative relation in which the best distribution of wax over the surface of the tool will be effected. In the illustrated arrangement the wax transferring wheel is mounted for axial adjustment with respect to the burnishing tool on a support which is rotatable about an axis substantially at right angles to the axis of the tool, to allow its positioning in the ultima relation to the tool, as well as being mounted for adjustment about an axis parallel to the axis of the tool, as has been customary in such machines, so that the wheel

may be moved toward and away from the tool.

It will be understood that, as the contours of various heels presented to a heel burnishing machine differ, it has been necessary either to apply differently shaped tools corresponding respectively to the contours of differently shaped heels, or to adjust the contour of the burnishing tool itself when, for example, the latter is of the type disclosed in Letters Patent of the United States No. 1,643,556, granted Sept. 27, 1927, upon my application. In either case, a longitudinal section through the axis of the tool shows frequently, and especially in the case of Louis heels, a contour such that the point of largest diameter lies between the ends.

Another feature of the invention, therefore, which is especially adapted to this condition but is also useful for all contours, resides in the provision of a plurality of wax transferring wheels, dipping in a wax pot, and arranged to be brought into operative engagement with the burnishing tool upon opposite sides of the point of greatest diameter. In the illustrated construction the wax wheels are adjustably supported so that the wheels and the tool may be relatively adjusted to bring them into proper interrelation, the wax wheels being mounted on a common axis and arranged for simultaneous adjustment about a plurality of axes. This common axis is journaled in the wax pot itself and the wax pot is mounted for adjustment not only about an axis parallel to the axis of the tool so that the wheels may be moved toward and away from the burnishing tool to regulate the transfer of wax, but is also mounted for adjustment about an axis substantially at right angles to the axis of the tool so that both wheels may be brought into the desired relation to the periphery of the tool for effective transfer of wax whatever its exact contour. This arrangement enables the transfer of wax to the tool along strips lying at either side of the bulge of the tool so that the action of centrifugal force urging the wax to the point of greatest diameter will assist in the wax distribution over the surface of the tool.

In accordance with still other features of the invention, the illustrated machine comprises a head and a base connected by a standard in which there is an upright shaft, and the machine is provided with a plurality of tool carrying shafts in the head upon opposite sides of said upright shaft, one of these being for the burnishing tool and another carrying the pad and the brush. As illustrated, too, means are provided for interconnecting the upright shaft with the tool carrying shafts which means are arranged to drive said tool carrying shafts in the same direction but at different speeds in order that they shall rotate at the speed most suitable for the tools which they carry. As illustrated, one tool carrying shaft is surrounded by a sleeve extending over a portion of its length which sleeve is connected at one end to the driving mechanism, and at the other end is arranged to supply power to the mechanism by means of which the carnauba wax is applied to and spread over the surface of the burnishing tool. Mechanism is also provided for interconnecting the sleeve with the tool carrying shaft which mechanism is constructed and arranged to impart an axial oscillation to the tool carrying shaft at it rotates said shaft, without, at the same time, oscillating the sleeve. This said oscillation of the shaft carrying the burnishing tool avoids the production of tool marks as is well understood.

Still another feature of the invention resides in the provision of a protective cover for the wax supplying mechanism which partially overlies the burnishing tool, and is provided with a hinged flap, the latter dropping down approximately to the surface of the tool to protect the operator from flying wax.

In the drawings, Fig. 1 is a side elevation of a burnishing machine embodying the invention, with parts broken away and in section.

Fig. 2 is a front elevation of the machine,

Fig. 3 is a plan view of the head of the machine with parts broken away and a cover removed to expose part of the driving mechanism,

Fig. 4 is a fragmentary plan view of a wax pot and the wax wheels with which the machine is provided and of driving mechanism for said wheels,

Fig. 5 is a fragmentary view, taken from the rear of the machine to show the driving mechanism for the wax wheels and a wax spreading brush,

Fig. 6 is an enlarged view, partly in section looking down on the shaft of the burnishing tool and its driving mechanism,

Fig. 7 is a rear view of the wax pot supporting bracket with the pot in section.

Fig. 8 is a vertical section through the wax pot taken from front to back.

The operating tools of the illustrated heel burnishing machine, including an adjustable burnished tool 10 of the type shown and

described in Letters Patent No. 1,643,556 above referred to, a pad brush 12, a bead wheel 14 and a polishing brush 16, are respectively mounted on a hollow shaft 18, and on solid shafts 20 and 22 journaled in a head 24 of the machine, and these operating tools are so positioned that the operator may with the minimum change of position, apply the work in sequence to said tools so as first to apply a coating of wax to the heel and to rub it in, then to spread out this wax and partially polish the coated surface by application of the heel to the pad brush 12, then to bead the heel by means of the beading wheel 14, and finally to complete the polishing of the work by application to the polishing brush 16.

Experience has shown that it is desirable to drive the various tools at different speeds by reason of their different functions but that they should be driven in the same direction so that the operator may with the maximum of convenience apply the work successively to said tools. The rotation of the tools is effected by power, supplied from any suitable source, such as an electric motor 26, which is transmitted to the tool carrying shafts through a drive shaft 28 mounted in the base of the machine and thence by means of a telescoping upright shaft 30 extending through a standard 32. The shaft 30 is connected to the shafts 18 and 20, respectively, by means of skew gears 34 and 36 (Fig. 2). These gears are arranged with a right and left hand twist respectively so that the shafts 18 and 20 may both be driven in the same direction but at different speeds determined by coating gears 38 and 40 connected to the shafts 18 and 20. In the arrangement shown, the speed of the tool shaft 18 is slightly less than that of the upright shaft 30, while the speed of the pad carrying shaft 20 is slightly greater than that of the upright shaft. On the other hand, it is desired to drive the beading wheel 14 at considerably greater speed than that of the pad and, accordingly, its shaft 22 is connected to the pad carrying shaft 20 by means of spur gears 42 and 44 having relative diameters such that the speed of the shaft 22 is greater and an idler 46 is interposed so that the beading wheel shaft 22 will rotate in the same direction as the shaft 20.

In the arrangement illustrated for use when the electric motor 26 provides the driving power, the motor shaft carries a spur gear 48 which meshes with an internal gear 50 carried on the drive shaft 28 and the drive shaft 28 is connected to the upright shaft 30 by means of mitre gears 52. The position of the head 24 may be adjusted vertically with respect to the standard 32 for the convenience of the operator, without interrupting the shaft driving connections, by means of a screw 54 (Fig. 2) bearing on the upper end

of the standard and threaded in the head 24. This adjustment is permitted by the telescoping of the two parts of the upright shaft 30, and after the head has been adjusted to the desired position, it may be clamped there by means of bolts 56 (Fig. 1). It may be desired to drive the machine by "factory power", as from a countershaft on the ceiling or floor, and in that case the motor 26 is removed and 10 a bracket (not shown) provided with fast and loose pulleys substituted and connected to the drive shaft 28.

If the burnishing tool 10 is of the adjustable type shown in Letters Patent No. 1,643, 15 556, to which reference has been made above it will have a series of individual work engaging elements which are relatively adjustable to vary the contour of the tool as a whole. Regardless of whether this adjustable type or 20 the type having a preformed contour is employed, the burnishing tool 10 may be heated by means of a gas flame (not shown), but is preferably heated electrically, as herein illustrated, by means of a cartridge unit 60 mounted 25 in the interior of the hollow tool carrying shaft 18 at the end of said shaft upon which the burnishing tool is supported. Current is supplied to said cartridge unit by means of leads 62 passing through shaft 18 and connected 30 at their outer ends by slip rings 64 (Fig. 2) and brushes (not shown) to a source of power. A control box of any suitable construction, such as the control box 66 which is of the type set forth in Letters Patent of the 35 United States No. 1,406,988, granted Feb. 21, 1922, upon the application of B. S. Lee, is supported upon a cover 68 for the head 24 and is provided with a control rheostat having a handle 70 and with a switch 72. It will be 40 noted that, for the convenience of the operator, the cover 68 is provided with a recess 74 in which a cleaning sponge or the like may be laid.

To coat differently shaped heels, the periphery of the burnishing tool 10 will have various contours and frequently, as in women's work, will be bulged so that its section of greatest diameter lies between the ends. The supply of wax to this periphery, 50 as is customary in machines of this type, comes from a wax pot 80 having therein an electric cartridge heating unit 82 by means of which wax may be melted and kept in a fluid condition. The melted wax in the wax pot 80 is transferred to the periphery of the tool 10 by means of a pair of constantly rotated wax transferring wheels 84 which are mounted upon a shaft 85 (Fig. 7) journaled in a bearing 86 integral with the wax pot 80. The heat of the wax pot is transferred 60 through the bearing 86 to the wax wheels 84. The provision of two wax wheels instead of one is of advantage in any case and, especially so when the tool has a bulged periphery for then the wax may be supplied to

the tool at points, i. e. along strips, separated a substantial distance in proportion to the length of the tool, and preferably lying upon opposite sides of the section having the greatest diameter. From these supplies the wax will be carried centrifugally over the periphery of the wheel as well as being positively spread out in the customary fashion and as later described.

Provision is made for relatively adjusting the position of the axes of rotation of the tool and the wax wheels so that the wax wheels may be brought into cooperative relation with the burnishing tool at the point or points at which the transfer of wax to the tool may be most successfully accomplished so as to get an even distribution over the whole surface of the tool. The positions of these transfer points will vary with the contour of the wheel and frequently will be adjacent to the portions of small diameter. In the arrangement herein shown, this adjustment is accomplished by providing an adjustable mounting for the wax pot itself in the form of a bracket 88 secured upon a rod 90 extending laterally from the head 24 of the machine in a direction parallel to the axis of the tool shaft 18. The bracket 88 is disposed beside another bracket 92 which is clamped to the rod 90 and has an upwardly extending portion (not shown) which is arranged to abut against a portion of the head 24 of the machine to resist turning movement of said bracket 92 and parts attached thereto. The bracket 92 also has a depending portion 94 arranged detachably to support a drip pan 96 (Fig. 1) as more fully shown and described in Letters Patent of the United States No. 1,636,333, granted July 19, 1927, upon the application 105 of J. F. Standish.

Adjustment of the position of the bracket 88, and hence of the wax pot and wax wheels 84 about the axis of the rod 90, so as to cause the wax wheels to move toward and away from the surface of the tool to vary the quantity of wax delivered to the tool, is effected by means of a slow motion means, such as a hand screw 98 which passes through the bracket 88 and bears against the body of the bracket 92. Having once been adjusted, the bracket 88 may be held in adjusted position by means of a clamping wheel 100 associated with a slotted segment 102 which hangs down from the bracket 88 alongside the depending portion 94 of the bracket 92.

In addition, provision is made for the adjustment of the wax pot 80 and, therefore, the wax wheels 84 about an axis substantially at right angles to the axis of the rod 90, and hence at right angles to the axis of the tool 10, by mounting the wax pot 80 upon an upright stud 104 which passes through a flange in the bracket 88 and is threaded in the bot-

bottom of the wax pot. This adjustment allows the wax wheels to be adjusted along the surface of the tool 10 and generally axially thereof to bring them into the desired relation to the tool and enables the angular relation between the axis of the wheels 84 and the axis of the tools to be varied in accordance with the shape of the tool so that said wheels 84 will coact evenly with the tool 10. The arrangement is such that the exact position of the wax wheels with respect to the axis of the stud 104 may be adjustably determined by means of a slow motion means in the form of a hand screw 106 passing through a portion of the bracket 88 into engagement with one side of a depending flange 108 upon the bottom of the wax pot to push it in one direction against the tension of a spring to be later described. The wax pot near its rear end is provided with a depending guide plate 110, which is slotted for the reception of a flattened finger 112, formed as an integral extension of the bracket 88, thus forming an interconnection between the bracket and the wax pot to steady the latter and providing for the attachment of a spring 114 by means of which the wax pot is normally swung in one direction against the action of the screw 106. By manipulation of the screw 106, the wax wheels may be adjusted axially of the tool to transfer their points of application of wax along the surface of the tool so as to get the most effective inter-relation regardless of the contour of the particular tool which is used. The adjustable arrangement of the dual wax wheel mechanism makes it adaptable for all the various contours which an adjustable tool of the type described in Letters Patent No. 1,643,556, to which reference has been made above may be given.

It will be seen that the wax pot 80 is provided with a lateral cup 116 which opens at its lower end into the interior of the wax pot and is utilized by the operator for the reception of a wire or the like, by means of which small quantities of wax may be applied to the work for the repair of scratches and imperfections. A cover 118 is mounted upon the wax pot and is provided at its forward end with a hinged, depending flap 120 which comes close to the upper side of the surface of the burnishing tool 10, thereby to protect the operator from flying wax. By this arrangement the depending flap 120 and the cover 118 may be thrown back together when it is desired to obtain access to the tool or to the wax supplying mechanism.

The driving mechanism for the wax wheels 84 is effected through an extensible shaft 122 provided with a plurality of universal joints 124 so that its operation will be unaffected by the adjustment of the position of the wax wheels. As a safeguard the shaft 122 is also provided with a slip joint 126 (Fig. 4) so that the mechanism will not be broken in case

an operator should try to start the machine before the wax has been melted at the wheels 84, as when the machine is being started in the morning. The slip joint 126 comprises a casing 128 in which is secured a cap member 130 attached to one part 132 of one of the universal joints 124. A short shaft portion 134 journaled in a bearing 136 upon the bracket 92 passes through one end of the cup-like casing 128 and has a head 138 surrounded by packing material such as leather, this head 138 being gripped more or less tightly to the cup-like casing 128 by means of a set screw 140.

The machine is also provided with a wax spreading brush 142 which, as illustrated, is constructed in accordance with the disclosure of Letters Patent No. 1,636,333, to which reference has been made above and which is arranged for reciprocation across the face of the burnishing tool 10 to spread out the wax which has been applied thereto by the wax wheels 84. To this end, spreading-brush holding mechanism 144 is mounted upon a rod 146 which is adapted to be reciprocated through a bearing 148 formed integrally with a protective casing 150 which surrounds the portion of the shaft 18 adjacent the burnishing tool.

Motion is transmitted to the wax-wheel driving shaft 122 from a rotary intermediate member, here an upright jack shaft 152 journaled in said protective casing 150 and connected to the portion 134 of said shaft by means of mitre gears 154. The jack shaft 152 is also connected to the rod 146 to reciprocate the latter by means of a crank and slotted block connection 156. In order that power may be supplied to the jack shaft 152 steadily but slowly to rotate it, said shaft is provided with a worm gear 160 meshing with a worm 162 which is formed on a sleeve 164 journaled in the head casing 24 concentrically with and surrounding the shaft 18. The skew gear 38, by means of which power is supplied from the upright shaft 30 to the tool shaft 18, is mounted directly upon this sleeve 164, being held there by any suitable device such as the set screws 166 and, by reason of suitable enlargements or collars upon the sleeve 164, is held against lateral oscillation with the shaft 18. Thus the sleeve 164 and hence the jack shaft 152 for driving the wax wheels 84 and the wax spreading brush 142 are rotated steadily without oscillation of the sleeve 164 and without that variation which would be found incidental to the drive of these mechanisms directly from the tool shaft 18. On the other hand, the transfer of power from the skew gear 38 to the shaft 18 is effected by means of a tongue 170 extending from a cam 172 which is secured to the shaft 18. This tongue 170 enters a slot in a hub portion of the skew gear 38 and hence is free to slide axially with respect

thereto. Axial reciprocation is imparted to the shaft 18 by the coaction of the cam 172 with a roller 174 fixed in the head casing 24 of the machine. The amount of axial movement is very slight, being simply sufficient to prevent the production of tool markings by the sections of the tool 10, and the curvature of the cam 102 is exaggerated in the drawings to make its function evident from an inspection thereof.

In order to avoid, so far as possible, the spattering of wax upon the operator, a suction hood 180, shallow so as not to interfere with free use of the pad 12, is associated with the brush pad 12, and this hood is provided with a receiving pan 182 at its lower end having a connection 184 by means of which an air suction pipe may be attached thereto. At the upper end of the suction hood 180 a notched flap 186 is provided by means of which pieces of wax carried around with the pad 12 by centrifugal force are caught and caused to drop into the receptacle 182 of the suction hood without being thrown upon the operator. The suction hood 180 is adjustably attached to lugs formed upon the bracket 92 by means of screws 188 passing through slots in the hood. The hood 180 is cut back as shown in Fig. 1 of the drawings in order to allow ready access to said pad wheel in applying work thereto and when it is desired to change the cloth cover on this brush.

The polishing brush 16 is also provided with a suction hood 190 having a pipe connection 192 at its lower end and at its upper end a fixed plate 194 extending toward the periphery of the brush in a more or less radial direction for the same purpose as the flap 186. This hood 190 is provided with a laterally extending flange 196, by means of which it may be attached to a portion of the head 24.

A tread rest 198 is adjustably supported by means of a slotted segment 200 and a clamping handle 202, to assist the operator in the proper presentation of the work to the burnishing tool 10. It will be seen from Fig. 3 that the beading wheel 14 is provided with a pivotally mounted friction heater 204 arranged to keep said wheel constantly hot so as to improve its effect upon the work.

In the operation of the illustrated machine, after wax has been melted and applied to the burnishing tool, and the machine has been started, the operator will present the heel of a shoe to the burnishing tool 10 with the tread face of the heel resting upon the tread rest 198 and the periphery of the heel bearing against the burnishing tool 10. By turning the heel, all portions of its peripheral surface may be brought into engagement with the surface of the tool 10. After the tool 10 has applied a coating of wax to the heel and has rubbed it thoroughly into the fibers of the leather of the heel, the shoe will

be transferred to the pad 12 and the wax thereby thoroughly spread out over the surface of the heel and partially polished. The same operation will also effect an evening of the wax coating and the removal of surplus wax in case more than the desired quantity of wax has been applied by the burnishing tool 10. The operator next, by applying the heel to the beading wheel 14, will cause a series of indentations to be made around the upper edge of the heel adjacent to the rand crease for decorative purposes. He then will transfer the work to the polishing brush 16 which is constructed of soft bristles so that it may be used to effect a final polishing of the work without injury to the upper of the shoe in case it contacts therewith.

Having thus described my invention, what I claim as new and desire to secure by Letters Patent of the United States is:—

1. In a machine for burnishing parts of boots and shoes, a burnishing tool, means for supplying wax to the periphery of said burnishing tool comprising a wax pot, a wheel dipping in said wax pot for transferring wax to the tool, and means for adjusting the position of said wheel axially of the tool so that it may be brought into co-operation with that portion of the burnishing tool at which the best distribution of wax over the surface of the tool will be effected.

2. In a machine for burnishing parts of boots and shoes, a burnishing tool, means for supplying wax to the periphery of said burnishing tool comprising a wax pot, a wax wheel journaled in said wax pot and arranged to dip in wax therein and to transfer wax to the surface of the tool, and means for adjusting the position of said wax pot and its associated wheel along the face of the tool thereby to vary the relation of the wheel to the tool to provide the most effective transfer of wax from one to the other.

3. In a machine for burnishing parts of boots and shoes, a burnishing tool having a contour corresponding to that of the surface to be operated upon, means for supplying wax to the periphery of said burnishing tool comprising a wax pot, a plurality of wax transferring wheels journaled therein and spaced apart a substantial distance in proportion to the length of the tool, and means for varying the angular relation between the axis of said wheels and the axis of the tool so as to bring both wheels into co-operative relation to the periphery of the tool irrespective of its contour.

4. In a machine for burnishing parts of boots and shoes, a burnishing tool, means for supplying wax to the periphery of said burnishing tool comprising a wax pot, a wax transferring wheel dipping therein and adapted to be brought into co-operative relation to the periphery of the tool, and means for adjusting the position of said wheel with

- respect to the tool about an axis substantially at right angles to the axis of the tool, thereby to bring the wheel and tool into the best wax supplying relation having regard to the contour of the tool.
5. In a machine for burnishing parts of boots and shoes, a burnishing tool, means for supplying wax to the periphery of said burnishing tool comprising a wax pot, a wax transferring wheel journaled in the wax pot and dipping therein, said wheel being arranged to be brought into cooperative relation to the periphery of the tool, and means for adjusting the position of the wax pot and wheel about an axis substantially at right angles to the axis of the tool.
10. In a machine for burnishing parts of boots and shoes, a burnishing tool, means for supplying wax to the periphery of said burnishing tool comprising a wax pot and a wax transferring wheel journaled in the wax pot and dipping therein, said wheel being arranged to be brought into cooperative relation to the periphery of the tool, and means for adjusting the position of the wax pot and wheel about an axis substantially at right angles to the axis of the tool.
15. In a machine for burnishing parts of boots and shoes, a rotatable burnishing tool, means for supplying wax to the periphery of said burnishing tool comprising a wax pot and a rotatable wax transferring wheel, and means for adjusting the burnishing tool and wax transferring wheel laterally of each other whereby they may be brought into cooperative relation.
20. In a machine for burnishing parts of boots and shoes, a rotatable burnishing tool, means for supplying wax to the periphery of said burnishing tool comprising a wax pot and a rotatable wax transferring wheel, and means for adjusting the burnishing tool and wax transferring wheel laterally of each other whereby they may be brought into cooperative relation.
25. In a machine for burnishing parts of boots and shoes, a rotatable burnishing tool, means for supplying wax to the periphery of said burnishing tool comprising a wax pot and a rotatable wax transferring wheel adapted to be brought into co-operative relation to the periphery of the tool, and means for relatively rotating said tool and said wheel laterally of each other, thereby to vary their co-operative relation.
30. In a machine for burnishing parts of boots and shoes, a burnishing tool, means for supplying wax to the periphery of said burnishing tool comprising a wax pot, a wax transferring wheel journaled therein and arranged to transfer wax to the periphery of the tool, and means for adjusting the said wax pot and wheel about two axes at right angles to each other.
35. In a machine for burnishing parts of boots and shoes, a burnishing tool, means for supplying wax to the periphery of said burnishing tool comprising a wax pot, a pair of wax wheels journaled therein, means for driving said wheels to transfer wax to the tool, and means for adjustably supporting said wax pot, constructed and arranged to tilt it about an axis substantially at right angles to the axis of the tool, thereby to bring both wheels into substantially equidistant relation to the surface of the tool, and means for also adjusting the wax pot about an axis parallel to the axis of the tool, thereby to regulate the approach of the wheels to the tool.
40. In a machine for burnishing parts of boots and shoes, a burnishing tool, means for supplying wax to the periphery of said burnishing tool comprising a wax pot, a bracket tiltable around an axis parallel to the axis of the tool, a pair of wax wheels mounted in a bearing on said bracket, said bearing being adjustable about an axis at right angles to the axis of the adjustment of the bracket, and slow-motion means for adjusting the position of the bracket and for adjusting the position of the wheel bearing whereby said wheels may be brought into the desired relation with the surface of the tool.
45. In a machine for burnishing parts of boots and shoes, a burnishing tool, means for supplying wax to the periphery of said burnishing tool comprising a wax pot and a plurality of wax transferring wheels dipping in said pot and spaced apart a substantial distance in proportion to the length of the tool, said wheels being arranged to co-operate with the periphery of the tool upon opposite sides of the point of greatest diameter.
50. In a machine for burnishing parts of boots and shoes, a burnishing tool, means for supplying wax to the periphery of said burnishing tool comprising a wax pot, a plurality of wax transferring wheels mounted on a common axis and spaced apart a substantial distance in proportion to the length of the tool, and means for simultaneously adjusting said wheels about an axis perpendicular to the axis of the wheels.
55. In a machine for burnishing parts of boots and shoes, a burnishing tool having a series of individual work engaging elements relatively adjustable to vary the contour of the tool as a whole, means for supplying wax to the periphery of said burnishing tool, said means comprising a pair of wax wheels spaced a substantial distance in proportion to the axial length of the tool, and means for adjustably supporting said wax wheels for rotation to transfer wax to the periphery of the tool, constructed and arranged to permit adjustment of the position of the wax wheels about an axis angularly related to the axis of the tool so that each of said wax wheels may be brought into the desired relation with the periphery of the tool regardless of the adjusted contour of the tool.
60. In a machine for burnishing parts of boots and shoes, a burnishing tool, means for supplying wax to the periphery of said burnishing tool comprising a wax pot, a pair of wax wheels journaled therein, means for driving said wheels to transfer wax to the tool, means for adjustably supporting said wax pot, constructed and arranged to tilt it about an axis substantially at right angles to the axis of the tool thereby to bring both wheels into substantially equidistant relation to the surface of the tool, and means for also adjusting the wax pot about an axis parallel to the axis of the tool, thereby to regulate the approach of the wheels to the tool.
65. In a machine for burnishing parts of boots and shoes, a burnishing tool, means for supplying wax to the periphery of said burnishing tool comprising a wax pot, a bracket tiltable around an axis parallel to the axis of the tool, a pair of wax wheels mounted in a bearing on said bracket, said bearing being adjustable about an axis at right angles to the axis of the adjustment of the bracket, and slow-motion means for adjusting the position of the bracket and for adjusting the position of the wheel bearing whereby said wheels may be brought into the desired relation with the surface of the tool.
70. In a machine for burnishing parts of boots and shoes, a tool shaft, a burnishing tool mounted thereon, means for imparting an axial and rotative movement to said shaft, auxiliary mechanism for controlling the ap-

5 plication of wax to the tool including a rotary driving member, and means associated with said shaft for turning said driving member and constructed and arranged for rotation with the tool carrying shaft but without axial movement therewith.

10 16. In a machine for burnishing parts of boots and shoes, a rotary shaft, a burnishing tool mounted on said shaft for rotation therewith, movable means for controlling the application of wax to said tool comprising a rotary intermediate member for driving said movable means, a sleeve surrounding said shaft and connected to said rotary driving member, and means for simultaneously rotating said sleeve and for rotating and imparting an axial reciprocation to said tool carrying shaft.

15 17. In a machine for burnishing parts of boots and shoes, a head and a base connected by a standard, a drive shaft in the base, an upright shaft passing through the standard, a plurality of tool carrying shafts in said head upon opposite sides of said upright shaft, and means for directly connecting said upright shaft to said tool carrying shafts to drive the tools in the same direction but at different speeds.

20 18. In a machine for burnishing parts of boots and shoes, a rotary burnishing tool, a wax pot, means for transferring wax from said wax pot to the tool, and a protective cover for the wax supplying mechanism provided with a depending flap which approaches the 25 upper side of the periphery of the tool, thereby to protect the operator from flying wax.

In testimony whereof I have signed my name to this specification.

GEORGE GODDU.
